UNITED STATES PATENT OFFICE.

JAMES HARRIS ROGERS, OF HYATTSVILLE, MARYLAND.

RADIOSIGNALING SYSTEM.

1,387,736.

Specification of Letters Patent. Patented Aug. 16, 1921.

Original application filed May 2, 1917, Serial No. 165,875. Patent No. 1,349,103, dated August 10, 1920.
Divided and this application filed March 8, 1920. Serial No. 364,224.

To all whom it may concern:

Be it known that I, JAMES HARRIS ROGERS, a citizen of the United States, residing at Hyattsville, in the county of Prince Georges 5 and State of Maryland, have invented certain new and useful Improvements in Radio-signaling Systems, of which the following is a specification.

My invention relates to radio signaling or 10 the sending and receiving of signals through space by means of electromagnetic waves, and it pertains particularly to the disposition of the radio conductor or conductors.

In the course of my experiments I have 15 discovered that grounded radio conductors or antennæ are highly efficient when disposed horizontally or substantially parallel to the surface of the earth, and surrounded by or inclosed in a uniform metallic screen 20 practically throughout their length, but insulated therefrom. The advantages of long prostrate (as distinguished from erect) antennæ are thus obtained and the objectionable effects of certain forms of static conditions are eliminated. 25

The invention as applied to the surface of the earth where there is land is described, illustrated and claimed in my pending original application Serial No. 165,875 filed May 30 2, 1917, (now Patent No. 1,349,103), of which the present application is a division. In said original application, the term "surface of the earth" was used to designate the surface where there is water as well as where 35 there is land, and the invention is therefore equally applicable to boats or vessels, particularly submarines, on which it is operative whether afloat or submerged.

The invention consists in the novel construction and arrangement of apparatus and parts thereof for sending and receiving radio signals hereinafter described and claimed, and illustrated in the accompanying drawings, in which drawings— 45

Figure 1 is a diagrammatic view of a boat or vessel, such as a submarine, equipped in accordance with the invention, receiving instruments being shown associated with the antennæ; and

Fig. 2 shows a conventional arrangement of sending instruments which may be substituted for the receiving instruments for transmitting signals.

Referring to the drawings, 10 indicates 55 the signal instruments, which in Fig. 1 are

those for receiving signals, while in Fig. 2 the instruments for sending signals are shown. In Fig. 1, 11 is a detector of any type, preferably an audion, 12 a telephone, and 13 and 14 the usual condensers. Any 60 desired type of instruments and arrangement of connecting circuits may be employed.

In Fig. 2 suitable sending instruments are conventionally shown. These comprise a 65 generator 15, transformer 16, spark gap 17, condenser 18 and key 19.

The above mentioned instruments are well known in the art of radio or magnetic wave signaling, and need not be further described. 70

20 and 21 are two antennæ extending in different directions from the signal instruments, and are shown associated with these instruments by inductive coupling, as coils 22 and 23 of a transformer. These 75 antennæ may extend in opposite directions, and in order to attain maximum efficiency, arrangement may be made so that they may be disposed in a line at right angles to the wave fronts when receiving.

The antennæ are each inclosed in a metallic screen shown as a metal pipe 24 in which the antenna is mounted by spacers or disks 25 of insulating material, such as porcelain, clay, fiber or the equivalent, so 85 that while each antenna is inclosed substantially throughout its length by the metallic screen it is insulated therefrom. At the outer end, or end away from the instruments, each antenna 20 and 21 is connected 90 to plates 26 and 27, respectively.

The length of each antenna may be selected to suit the condition under which each system is to work, and may be several hundred feet or more. The pipe or screen may 95 be of iron or other metal suitable to accomplish the purpose, and serves to protect the antenna from certain static conditions which would, or might, interfere with the sending or receiving of signals.

In the present embodiment of the invention, it will be seen that the antennæ with appropriate screens are mounted within a vessel indicated at 28, this vessel being shown as a submarine. The screens 24 are preferably extended through the sheathing or hull, so that each antenna is inclosed substantially throughout its length within the vessel. The ground plate 26 at the forward end of the vessel is preferably pivotally mounted at its 105 110

forward edge on brackets 29, 30, so as to swing freely with the movement of the vessel, but is insulated therefrom, as shown diagrammatically at 31, 31. This antenna 20 is connected to plate 26 in any suitable manner. Ground plate 27 is similarly mounted on brackets 29', 30', at the stern of the vessel, and is connected to antenna 21. These plates may be mounted in any other suitable 10 manner.

In the use of the invention, the pipe or screen is preferably filled with oil such as is ordinarily used in transformers, for the purpose of preventing brush discharge.

15 The details of construction and arrangement of the pipe or screen containing the spacing elements, the antennæ, and the oil, are as illustrated in the application of which the present application is a division, 20 and it is therefore thought that further illustration in the present case is unnecessary.

It will thus be seen that I have provided a vessel, such as a submarine, with radio 25 signal receiving and sending apparatus associated with a conductor extending longitudinally thereof, substantially the full length of the vessel. It will also be observed that this conductor with which the signal instruments are associated is inclosed substantially throughout its length within said vessel, and therefore when the vessel is a submarine, and is running submerged, the conductor is insulated from the water substantially 30 throughout its length.

In accordance with the present statutes I have described what I now believe to be the best embodiment of the invention, but I do not wish to be understood thereby as limiting myself or the scope of the invention, as 40 many changes and modifications may be made without departing from the spirit of the invention, and all such I aim to include in the scope of the appended claims. For 45 instance, each antenna is shown as a single wire or conductor, whereas it might be composed of multiple conductors.

Having described my invention, what I claim as new and desire to secure by Letters 50 Patent of the United States, is:

1. The combination with a vessel having a metallic hull, of an antenna extending substantially horizontally and inclosed substantially throughout its length within said hull, 55 and electromagnetic wave signal instruments associated with said antenna.

2. The combination with a submarine vessel having a metallic hull, of an antenna operative when the vessel is afloat or submerged extending longitudinally thereon substantially horizontally and inclosed substantially throughout its length within said hull, and electromagnetic wave signal instruments within said vessel associated with said 60 antenna.

3. The combination with a vessel having a metallic hull, of a radio conductor extending longitudinally thereof substantially from one end of said vessel to the other and having its ends located substantially at the 70 respective ends of the vessel, and radio signal instruments associated with said conductor at a point between the ends of the conductor respectively at the ends of the vessel.

4. The combination with a vessel having a 75 metallic hull, of a radio conductor extending longitudinally thereof substantially from one end of said vessel to the other and having its ends located substantially at the respective ends of the vessel, and radio 80 signal instruments associated with said conductor at a point substantially intermediate the ends of the conductor respectively at the ends of the vessel.

5. The combination with a submarine vessel 85 having a metallic hull, of a radio conductor extending longitudinally thereof substantially from one end of said vessel to the other and having its ends located substantially at the respective ends of the vessel, 90 and radio signal instruments associated with said conductor at a point between the ends of the conductor respectively at the ends of the vessel.

6. The combination with a submarine vessel 95 having a metallic hull, of a conductor extending longitudinally thereof and insulated substantially throughout its length except at its ends adjacent the respective ends of the hull from the water when the vessel is 100 submerged, and radio signal instruments associated with said conductor.

7. The combination with a metallic submarine vessel, of an antenna extending longitudinally thereof and inclosed substantially 105 throughout its length within said vessel, and radio signal instruments associated with said antenna.

8. The combination with a vessel, an antenna thereon extending substantially horizontally, electromagnetic wave signal instruments associated with said antenna at one end and a ground connection through the water at the other end, and a metallic screen inclosing said antenna substantially throughout 115 its length within the vessel.

9. The combination with a vessel, electromagnetic wave signal instruments thereon, an antenna on said vessel extending substantially horizontally and with one end of 120 which said instruments are associated, a ground connection through the water at the other end of said antenna, and a metallic screen inclosing said antenna substantially throughout its length within the vessel and 125 extending without the vessel.

10. The combination with a submarine vessel, an antenna thereon extending substantially horizontally, electromagnetic wave signal instruments associated with said an- 130

- tenna at one end and a ground connection through the water at the other end, and a metallic screen inclosing said antenna substantially throughout its length within the vessel. 5
11. The combination with a submarine vessel, an antenna thereon extending substantially horizontally, electromagnetic wave signal instruments associated with said antenna at one end, a metallic screen inclosing said antenna substantially throughout its length within the vessel, and a ground plate mounted without the vessel but insulated therefrom and with which said antenna is 10 associated. 15
12. The combination with a vessel, an antenna thereon extending substantially horizontally, a second antenna extending in a different direction, electromagnetic wave signal instruments connected between said antennæ, a metallic screen inclosing said antennæ substantially throughout their length within the vessel, and a ground connection for each antenna through the water. 20
- 25 13. The combination with a vessel having a metallic hull, of a radio conductor extending longitudinally thereof substantially from one end of the vessel to the other and having its ends grounded, and radio signal
- instruments associated with said conductor 30 at a point between its ends. 35
14. The combination with a vessel, of an antenna therein extending substantially horizontally, electromagnetic wave signal instruments associated with said antenna, and a metallic screen inclosing said antenna substantially throughout its length. 40
15. The combination with a vessel having a metallic hull, of a radio conductor extending longitudinally thereof substantially from one end of the vessel to the other and having its ends grounded, radio signal instruments associated with said conductor at a point between its ends, and a metallic screen inclosing said conductor. 45
16. The combination with a vessel having a metallic hull, of a radio conductor extending longitudinally thereof substantially from one end of the vessel to the other, electromagnetic wave signal instruments associated with said conductor at a point between its ends, and a metallic screen inclosing said conductor substantially throughout its length and making electrical connection with the respective ends of the vessel. 50 55

In testimony whereof I affix my signature.

JAMES HARRIS ROGERS.
